[57] CLAIM

The ornamental design for a lavatory handle, as shown and described.

DESCRIPTION

FIG. 1 is a top perspective view of a lavatory handle showing my new design;
FIG. 2 is a top plan view thereof;
FIG. 3 is a left side elevational view thereof, the right side being a mirror image of the left side shown;
FIG. 4 is a front elevational view thereof, the near view being a mirror image of the front view shown; and
FIG. 5 is a bottom plan view thereof.

FIG. 1

FIG. 2

FIG. 3

FIG. 4

FIG. 5
